POLYPHASE PROTECTIVE SYSTEM

Robert P. De Anthony, Dayton, Ohio

Application June 30, 1944, Serial No. 542,995

1 Claim. (Cl. 177—311)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to improvements in protective systems for electrical apparatus, and more particularly to a protective system for interrupting the flow of current between a current source and an electrically operable apparatus through a plurality of electrical conductor lines, incident to the interruption of current flow in any one of the conductor lines.

An object of the present invention is to prevent continued operation of a polyphase dynamoelectric machine in the event of failure of any of the phases where such failure is insufficient to prevent continued operation on the remaining phases.

A further object of the present invention is the provision of simple and effective automatic circuit breaking means for a plurality of electrical operating circuits, each having an overload fuse device therein, including independent shunt circuits for actuating the circuit breaking means when energized, said shunt circuits being bridged across the fuse devices so as to be energized by failure of the fuse device to cause operation of the circuit breaking means to break all of said electrical operating circuits incident to the interruption of any one of said operating circuits by the fuse device therein.

A further object is the provision of a protective system for polyphase dynamoelectric machines, such as multiphase motors and the like, having a plurality of phase lines each protected by a fuse device, and connected to a current source and to the phase windings of the motor device, and including normally open circuit closing switch means controlling the current flow in all of the phase lines, movable to circuit closing position, having a holding coil and an energizing circuit therefor provided with circuit breaking means and a plurality of operating shunt circuits for the circuit breaking means each bridged across one of the fuse devices in each phase line to energize one of the shunt circuits to actuate the circuit breaking means to break the holding coil circuit incident to interruption of the circuit in one of the phase lines by the fuse device in that line.

A further object is the provision of releasable locking means for the magnetic circuit breaking means for locking the same in circuit breaking position.

A still further object is the provision of an

electrically actuated signal device for the magnetically operated circuit breaking means, adapted to be actuated incident to the energizing of the magnetically operated circuit breaking means.

5 A still further object is the provision of a simple and effective circuit interrupting device for breaking the main switch holding circuit of a conventional polyphase dynamoelectric machine control system, operable upon interruption of 10 current flow in one of the phase lines by a fuse device in that line and controlled by a shunt circuit in that line around the fuse device to break the main switch holding circuit, releasing the main switch to cause interruption in the current 15 flow in all of the phase lines between the electrical power source and the polyphase dynamoelectric machine.

Other objects and advantages of the invention will become apparent from the following description, 20 taken in connection with the accompanying drawings in which like reference characters refer to like parts on the several figures of the drawings.

Fig. 1 is a side elevation, partly broken away 25 and shown in section, of my improved polyphase circuit protective device, showing the same connected schematically in a conventional polyphase dynamoelectric machine starting and control circuit.

Fig. 2 is a top plan view of my improved circuit breaker device.

Fig. 3 is a fragmentary sectional view taken approximately on the plane indicated by 3—3 of Fig. 1.

35 Referring more particularly to Fig. 1 of the drawings, the numeral 1 indicates schematically a polyphase dynamoelectric machine, such as a three phase motor having the phase winding or field coils 2, 3, 4 thereof connected respectively 40 by phase lines 5, 6, 7 to one terminal of each of the circuit closing devices or switches 8, 9, 10. These switches are preferably of the "gang" or simultaneously operable, normally open type, having a common actuator 11 and a closing and holding circuit including a closing and holding magnet coil 12. Current is supplied from a conventional polyphase electrical source (not shown), through the phase lines 13, 14, 15, each protected 45 by individual overload fuses or circuit breaking devices 16, 17, 18, connected to the lines 19, 20, 21, which are in turn connected to the other terminal or contact of each of the respective switches 8, 9 and 10. Thermal relays 19a and 21c are usually interposed in the lines 5 and 7 ahead of 50 the switch contacts 8 and 10 for the purpose of

preventing the motor windings or other parts of the system from being burned out or damaged in the case of a serious overload. These thermal relays usually are of the bi-metallic type and are therefore apt to be quite sluggish in action, so that when a main fuse in one of the phase lines blows out, the motor or other device may continue to operate on the remaining phase lines in an unbalanced phase relation causing excessive heating, and, if the other phase lines are not interrupted very promptly, serious damage to the motor or other apparatus being operated may result. Should the bi-metallic relays fail to function, which may be the case where the motor load is light, this vibration and heating will do irreparable damage to the motor. Also it is necessary that these relays be of the proper rating for the particular motor used, which requires a different size relay when a different size motor is operated in the circuit.

Customary stop and start push buttons 22 and 23 are disclosed, which are ordinarily connected by a conductor 25 (shown in dotted lines) to one side of the holding coil 12 by the wire 12a, and to one side of the start and stop push button contacts by a conductor 26. Depression of the starting button 22 closes a holding circuit through the wires 27, 21 and fuse 18 of the feed wire 15 while current from the feed wire 13 passes through the fuse 16, conductor 19, conductor 19a, holding coil 12, conductors 12a, 25 and 26, through the switch contacts 22a of the starting switch 22 and through the conductors 27, 21 and fuse 18 to the other main feed wire 15 to complete the starting circuit. As before indicated, this circuit is a conventional polyphase motor starting circuit, and is inclosed by the phantom line in Fig. 1. My protective system modifies this circuit in a manner later to be described.

When the starting coil 12 is energized, this causes the common switch actuator 11 for the normally open phase line switches to close, establishing the phase circuits through the lines 13, 14 and 15 to the field windings 1, 2 and 3 of the dynamoelectric machine 1. Closing of the switch 10 establishes the holding circuit from the main line 15 through the fuse 18, conductors 21, 21a, thermal relay 21c, switch 10, conductors 7 and 28 through the normally closed contacts 23a of the stop switch 23 and conductor 30 to the conductors 26, 25 and 12a, back to the starting and holding coil 12. Completing this conventional starting and holding circuit, current then flows from the starting and holding coil 12 through the conductors 19a, 19, fuse device 16 to the other main feed line 13.

In my improved polyphase protective system I provide an electrically operable circuit breaker, indicated generally at 31, later to be described in detail, having circuit breaker contacts interposed in the starting and holding coil circuits above described. The conductor 25 is removed and the conductor 12a is connected by a wire 32 to one side of the circuit breaker contact means of the circuit breaker 31 while the other side of the circuit breaker contact means is connected by a conductor 33 to the conductor 26 leading to the contacts 22a and 23a of the starting and stopping switches 22 and 23. Energization of the circuit breaker, separating the circuit breaker contacts, interrupts both the starting and holding circuits.

The circuit breaker 31 is provided with a plurality of independent breaker energizing or operating circuits 34, 35 and 36, each connected in shunt across one of the respective thermal re-

sponsive elements or fuse devices 16, 17 and 18 in the phase lines 13, 14 and 15.

Since the fuses or thermal responsive elements 16, 17 and 18 are of comparatively low impedance, there will be only a very negligible current flow through the shunt circuits 34, 35 and 36, which will be well below the amount necessary to operate the breaker device 31 to interrupt the starting and holding circuits.

In the event of an excessive overload or short circuit in any one of the phase lines or the dynamoelectric device connected thereto (shown in the drawings for the purpose of illustration only as a three phase circuit), one of the thermal responsive circuit interrupters or fuse elements 16, 17 or 18 in the overloaded line will function to interrupt the current in that line, causing current to flow through the shunt circuit associated with the fuse device in that line, energizing the circuit breaker 31 to break the starting and holding circuits. The common switch actuator 11 being thus released by the breaking of the circuit to the holding coil 12, the switch actuator 11 will move to circuit breaking position, interrupting current in all phase lines between the current source and the dynamoelectric machine 1.

An annunciator or other signal device 37 of any well known electrically operable type is preferably provided, having an independent energizing circuit 38 adapted to be energized as an incident to the circuit breaking operation of the circuit breaker 31.

More specifically describing the circuit breaker 31, I provide a plurality of end supports 39, 40, carrying a conventional laminated core 41 fixed therein. A plurality of exciting coils 42, 43 and 44 are superimposed on the core, as best seen in Fig. 1, each coil being connected in one of the shunt circuits 34, 35 and 36. An additional induction coil 45 is disposed between the two supports 39, 40 next to the core, and connected in the independent energizing circuit 38 for the signal device 37.

The opposite ends of the core member 41 are bridged by U-shaped contact supporting members 46 and 47, carrying insulated electrical contacts 48, 49, 50 and 51. Contact 48 is connected to the conductor 32 leading from the holding coil 12 while the contact 51 is connected to the conductor 33 leading to the stop and start switch contacts 23a and 22a.

Armature members 52 and 53 are movably disposed in the U-shaped portions of the respective end members 46 and 47 on fixed guide rods 54 and 55, the ends of the rods 54, 55 having their ends disposed in suitable sockets in the respective end supports 39 and 40 and in the U-shaped supports 46 and 47. Each armature carries a pair of electrically connected contacts, indicated at 56, 57 and 58, 59 in Fig. 2, adapted to engage the respective stationary contacts 48, 49 and 50, 51, when the armatures are spaced away from the ends of the core member 41. Resilient actuating means in the form of coil springs 58 are disposed on the guide rods 54, 55 between the end supports 39 and 40 and the armatures 52 and 53 to yieldably urge the armatures away from the core 41 and to move the respective circuit closing contacts into circuit closing engagement.

Locking means are provided for releasably holding the circuit breaking contacts in circuit breaking relation as shown in dotted lines in Fig. 3 after the armatures have been moved toward the ends of the core 41.

A bridging conductor 59 connects the station-

ary contact 49 to the stationary contact 50, providing the circuit breaker device with four circuit breaking contacts connected in series, any one of which when moved to circuit breaking position, due to energization of the core by one of the shunt circuits in the phase lines, will interrupt the holding circuit, permitting the switch actuator to move to circuit breaking position and interrupt the phase current flowing to the motor field coils.

The releasable locking means for holding the armatures in circuit breaking positions comprises locking abutments, each in the form of a pin or rod 60, fixed to and projecting from the face of each armature 52, 53, intermediate the spaced armature contacts thereon. These abutments or pins 60 are slidably received in the guide recesses 61 formed in the U-shaped cross members 46 and 47. Lateral passages 62 extend vertically into the guide recesses 61, each carrying a locking detent member 63, adapted to rest against the side of one of the locking rods or pins 60 when the armatures are in circuit closing position.

Movement of the armatures toward the core member axially displaces the locking pins 60 out of the path of the locking detent members 63, allowing the detent members 63 to move upwardly into the path of return movement of the locking pins 60, blocking the return movement of the armature members under influence of their actuating springs 58, toward the starting and holding circuit closing contacts 48 to 51.

The locking detent members 63 each have a U-shaped operating extension or handle portion 63a extending upwardly through a bore 64, parallel to the passage 62 in the U-shaped support, and the extremities of these extensions are pivotally connected, as indicated at 65 and 66, to the opposite ends of a common resetting bar member 67 having a resetting or operating button 68 centrally mounted thereon. Guideways or slots 69, 69 are formed in the upper edges of the end supports 39 and 40, and in the upper edge of a separator plate 70, for receiving the resetting bar member 67 and maintaining the same slideable in a vertical plane. Each operating extension or handle 63a is provided with an enlarged abutment 71 intermediate its length for engagement with one end of a release coil spring 72. These springs are interposed between the abutments 71 and the top surfaces of the U-shaped support or end members 46, 47 to urge the respective detents upwardly into locking position.

When one of the armatures 52 or 53 is attracted, incident to energization of one of the shunt circuits 34, 35 or 36, the pin 60 carried by the armature is moved out of the path of the locking pin 63. The spring 72 on the vertically movable locking pin extension 63a raises the locking pin 63 into the path of movement of the armature carried locking pin 60, preventing return of the said contact carrying armature 52 or 53 to circuit closing position. This locking movement of the pin or pins 63 elevates one or both ends of the release bar and its resetting button, depending whether one or both armatures have been actuated.

To reestablish the phase circuits to the polyphase dynamoelectric machine, the reset button 68 is first depressed, withdrawing the vertically movable locking pins 63 out of the path of movement of the locking rods 60 carried by the armatures 52, 53. The springs 58 on the guide pins 54 and 55, as best seen in Figs. 2 and 3, now space the armatures away from the poles of the

core member 41 and into circuit closing position with respect to the starting and holding coil contacts 49 to 51 and 56, 57. This moves the locking pins 60 into the path of return movement of the vertically movable locking pins 63, thus locking the reset bar and button in depressed position with the circuit closed, as shown in full lines in Fig. 1. Assuming that the cause of the overload in the phase line has been remedied, and the blown fuse device in the previously overloaded line has been replaced, depression of the starting button 22 energizes the starting coil 12, closing the switches 8, 9 and 10 to all of the phase lines.

The signal device 37, as disclosed in the drawings, comprises a support 75 having a drop type annunciator lever 76, carrying an annunciator plate 77 having an appropriate signal legend thereon, such as "Fuse out." A spring loaded release latch in the form of an armature 78 is pivoted to the support 75 to engage the end of the legend plate 77 holding the same out of view until released by an electro-magnet device 79 electrically connected in the closed induced current circuit 38 having the induction coil 45 of the circuit breaker 31 also in the circuit. Any current flowing through any of the shunt circuits 34, 35 and 36, due to the "blowing" of a fuse device in one of the phase lines 16, 17 and 18 energizes one of the respective magnet coil 42, 43 or 44 of the circuit breaker device 31, attracting one or both of the circuit breaking armatures 52 or 53, toward the ends of the core. The locking pins 60 being displaced out of the path of the vertical locking pins 63, these latter pins move across the guide bores 61 for the locking pins 60, preventing the return of the armature or armatures to circuit closing position until the reset button 68 is depressed.

A voltage is induced in coil 45 causing an induced current to flow in the signal circuit 38, energizing the magnet 79, displacing the latch 78 to drop the signal 77 to the dotted line position in Fig. 1.

Since the fuse devices 16, 17 and 18 are all of comparatively lower impedance while the shunt circuits 34, 35 and 36 of the breaker device are of relatively high impedance, my improved protective system and apparatus may be employed substantially without change in any conventional polyphase dynamoelectric machine control circuit, the only requirement being that overload fuse devices of the proper ratings be provided for the motor or other operated device being used be placed at 16, 17 and 18 in the respective phase lines 13, 14 and 15.

The thermal relay devices 19a and 21c are disclosed as a part of a conventional polyphase dynamo-electric machine starting and holding circuit, but in my improved protective system these thermal relay devices may be dispensed with since they are unnecessary to the operation of the system.

The circuit breaker device 31 is preferably housed in a suitable metallic housing or case (not shown) having an opening therein for access to the reset button 68 while the signal indicator 37 may be located at any desirable remote location.

Although one specific embodiment of the invention has been shown and described it will be understood that the invention is capable of modification, and that changes in the construction and arrangement of the various cooperating parts may be made without departing from the spirit of the invention as defined in the accompanying claim.

I claim:
1. In a polyphase dynamoelectric machine protec-

tive apparatus, a plurality of phase lines adapted to be connected to a polyphase dynamoelectric machine, a thermal responsive element in each phase line for interrupting current flow incident to overload in that line, magnetically operable circuit closing and holding means for closing all phase circuits and releasably maintaining the same in closed position including a closing circuit and a holding circuit for energizing said magnetically operable circuit closing and holding means, a support, a core, an independent exciting coil on said core for each phase line connected in shunt across the thermal responsive overload device in that line, an electrically operable signal device and an additional induction coil on said core having a closed operating circuit including the electrically operable signal device, circuit closing armature

means movably mounted to be actuated by said core, cooperating circuit closing contacts carried by said armature and support disposed in said holding circuit, spring means between the support and armature to yieldably space the same from said core, with the closing contacts engaging each other to close the holding circuit, and releasable latching means between the support and armature for holding the armature and contacts in circuit breaking position after attraction thereof by said core incident to energization of one of said shunt circuits due to current interruption of current flow in one of said phase lines by the thermal response overload element in that line.

ROBERT P. DE ANTHONY.
